UNITED STATES PATENT OFFICE.

GEORGE STABER AND HARTWELL ABBEY, OF BROOKLYN, NEW YORK.

MACHINE FOR EMBOSSED OR ORNAMENTING WOOD, PAPER, &c.

SPECIFICATION forming part of Letters Patent No. 451,983, dated May 12, 1891.

Application filed September 6, 1890. Serial No. 364,168. (No model.)

To all whom it may concern:

Be it known that we, GEORGE STABER and HARTWELL ABBEY, citizens of the United States, residing at Brooklyn, in the county of 5 Kings and State of New York, have invented certain new and useful Improvements in Machines for Embossing or Ornamenting Wood, Paper, and other Materials; and we do declare the following to be a full, clear, and exact description of the invention, such as will enable others skilled in the art to which it appertains to make and use the same.

The present invention relates to machines for embossing or charring wood and other 15 substances for the purpose of ornamenting the surface thereof; and the improvements relate, primarily, to the mechanism by which the pressure-roll is held up to or against the stock or work by the direct application of the 20 force of a spring, and at the same time the relative position of the pressure-roll to the design-roller is subjected to the regulative action of an adjusting-screw to accommodate the rollers to stock or work of different sizes.

25 With these ends in view our invention consists of the combination and construction of parts, as will be hereinafter fully described and claimed.

To enable others to understand our invention, we will proceed to a detail description thereof in connection with the accompanying drawings, in which—

Figure 1 is an elevation of a machine for embossing wood and other material constructed 35 in accordance with our invention. Fig. 2 is a detail sectional view of the means for applying spring-pressure directly to the pressure-roll for regulating the position of said roll relatively to the design or embossing roll.

40 Fig. 3 is a detail view of a modified form of the pressure and regulating device. Fig. 4 is a perspective view of the vertically-adjustable frame for supporting the pressure-roll. Fig. 5 is a detail view of the devices for sup-

45 porting the design or embossing roll and permitting its ready removal and replacement, showing the cap-piece B thrown back. Fig. 6 is a similar view of the opposite side of the devices, showing the cap-piece let down. Fig.

50 7 is a perspective view of the cap-piece removed. Fig. 8 is a perspective view of the

table for supporting the stock, showing the same in connection with the frame for supporting the pressure-roll and also showing on the table the adjustable strips for guiding the 55 stock; and Fig. 9 is a sectional detail view of said table, showing one of the guide-strips in position.

Like letters and numerals of reference denote corresponding parts in all the figures of 50 the drawings, referring to which—

A designates the main frame, which comprises the fixed base *a* and the uprights or standards *b b'*, arranged in two pairs, one pair being on each side of the machine.

65 B is the upper or design roller, and C is the lower or pressure roll.

As is usual in this class of machines to which our invention relates, both the upper and lower rolls are made hollow and suitable 70 for the admission of pipes or burners which are provided for supplying hot-air or gas heat to the interiors of the rolls for the purpose of highly heating the same; but as no novelty is herein claimed on the means for heating said 75 rolls we have not deemed it essential to illustrate the means employed for that purpose.

The upper roll B is provided with an encircling band B', containing the pattern or ornamentation it is desired to impart to the 80 work or stock; or, if desired, two or more pattern-bands may be placed on the rolls. The said upper roll has its hollow trunnions *c* journaled in the fixed bearings or bridge-piece C' between the uprights of the main frame, and 85

in order to secure the roll in the bearings, and at the same time permit of the ready release of said roll and its expeditious removal from the frame, we provide the adjustable cap-piece D, one at each side. This cap-piece has 90

at one side the lugs *d*, which are pivoted to one of the standards of the frame, and at the free end of said cap-piece we provide the bifurcated lug *d'*, which is adapted when said 95

cap is lowered into position between the standards to embrace the other standard *b* of the pair of standards, a pivoted lever or catch E being provided on said standard *b'* to take over the lug *d'*, and thus lock or confine the swinging cap D in place. The cap is recessed 100 or concaved on its lower edge to snugly fit over the hollow trunnions of the roll, and it

is obvious that when the roll is to be removed the only adjustment required is to release the locking lever or catch E and swing the cap upward and backward out of the path of the roll. The upper roll can then be easily removed from the main frame to change the design band or bands thereon, and it can be replaced with great ease and facility, which is highly desirable in this class of machines, 10 where the patterns are quite frequently changed.

In embossing-machines for ornamenting wood which employ a stationary upper design-roller it is essential to provide a lower pressure-roller which constantly bears against the stock with a given uniform pressure, and which lower roll can be varied in relation to such design-roller to accommodate stock of different thicknesses or sizes.

20 In our improved machine we provide a simple and compact device which applies the necessary pressure to the pressure-roll direct from a spring, and the relative position of such roll is regulated by a screw, the detail 25 construction of which devices are as follows: A vertically-adjustable frame F is employed for supporting the lower roller C, and this frame is substantially yoke-shaped, as indicated in Fig. 4 of the drawings, said frame 30 consisting of the vertical sides f f and the transverse bridge-piece g, all of which constitute a single casting. The sides f f are recessed or grooved vertically to adapt the standards b b to fit snugly into the frame, 35 and thus guide the frame F in its vertical movements in the main frame, and the upper edges of its side are concaved at f' to form the bearing for the hollow trunnions of the pressure-rolls. In the center of the bridge 40 g of this adjustable frame we provide a vertical aperture h, and through this aperture passes the upper end of a vertical lifting rod or bar I, arranged in about the vertical center of the machine. In the preferred embodiment of this part of our invention (shown in 45 Figs. 1 and 2 of the drawings) we screw-thread the upper part of this vertical lifting rod or bar and pass the screw-threaded portion loosely through the hole in the adjustable frame, 50 and the lower end of the rod or bar is passed through a hole in the base of the frame, through which it moves vertically, the rod having a spline, as shown, which takes into a corresponding groove in the hole of the base, 55 whereby said rod may be prevented from turning as a screw.

The screw-threaded bar serves to transmit the pressure or force of the coiled spring to the adjustable frame, because the spring bears 60 against the base of the main frame, and the upper hand-wheel 3 bears against the lower side of the adjustable frame.

The height of the adjustable frame can be varied simply by turning the upper hand-wheel 3 in the desired direction to raise or lower said frame and the pressure-roll, accord-

ing to the size of the stock it is desired to feed to the machine, while the tension of the spring and the pressure of the lower roll upon the stock can be varied by simply adjusting the 70 lower hand-wheel 2, said wheel 2 being lowered on the threaded lifting-rod if it is desired to compress the spring and increase the tension thereof, or raised when desired to slacken the spring and reduce the pressure of the 75 lower roll against the stock.

In Fig. 3 we illustrate a modification of our invention in which we employ a single hand-wheel on the threaded rod and place the pressure-spring between the hand-wheel and 80 the adjustable frame, so that the pressure of the coil-spring is applied directly to the yoke-shaped frame. At the same time the elevation of the frame F can be varied and the tension of the coiled spring thereon regulated 85 by the simple adjustment of the hand-wheel on the screw.

The operation and advantages of our invention will be readily understood and appreciated by those skilled in the art to which 90 it relates from the foregoing description, taken in connection with the drawings.

By special reference to Fig. 8 of the drawings it will be seen that we have provided a support or table for the stock, which is designed to extend on opposite sides of the machine in a similar manner, and which, being secured to the frame F, carrying the pressure-roll, will adapt itself to the upper surface of said roll by moving with the latter, and, being 100 sustained alike under yielding pressure, will accommodate itself to the thickness of the material. This table is composed of two similar side bars L, having their longitudinal central portions M provided with holes or the 105 like for the reception of bolts or other suitable devices to fasten the same to the outer sides of the side pieces of the frame F. These bars L are thence carried outwardly in opposite directions, as shown, and terminate in 110 horizontal branches N, which are elevated to an altitude approximating that of the surface of the pressure-roll.

P indicates slotted cross-bars carried by the elevated portions of the table-frame. The 115 slotted bars are designed to receive the shanks of set-nuts Q, which are secured in one end of guide-strips R, and by means of said nuts the strips may be moved to and from each other and secured in any desired position 120 upon the tables. The strips R are designed to serve as guides for the stock operated upon as it enters and leaves the machine.

While we have shown threaded rods and 125 nuts for setting up and adjusting the guide-strips, yet other suitable means might be employed for that purpose.

We attach importance to the construction of the double table and to the fact that it is secured to the frame carrying the pressure-roll, so that any movement of one will cause 130 a corresponding and synchronous movement

of the other, thereby sustaining the stock in proper position with respect to the surface of the pressure-roll.

Having described our invention, what we claim is—

1. In a machine for embossing wood and other material, the combination, with an embossing or design roller and a pressure-roll, of a vertically-movable frame supporting said pressure-roll, a threaded rod bearing in the main frame and arranged directly beneath said movable frame, a coiled pressure-spring fitted on said rod, and a hand-wheel also fitted on the rod, whereby said frame and pressure-roll may be moved vertically and sustained yieldingly, substantially as specified.
2. In a machine for embossing or ornamenting wood and other materials, the combination, with an embossing or design roller and a pressure-roll carried by an adjustable frame, of a threaded lifting-rod arranged centrally to the adjustable frame, a coiled pressure-spring fitted on said rod, and the independent hand-wheels both fitted on the lifting-rod,

one wheel being in direct contact with the 25 adjustable frame to positively move the same and the other wheel bearing against the pressure-spring for the purpose of varying the tension thereof, substantially as described.

3. In a machine for embossing or ornamenting wood and other materials, the combination, with an embossing-roll, of a pressure-roll, the adjustable frame in which said pressure-roll is journaled, provided with a central aperture, the vertically-movable threaded rod 30 fitted in the aperture of said frame, the coiled spring fitted on the rod, and the independent hand-wheels, both fitted on the rod and one arranged in contact with the adjustable frame and the other engaging the spring, substantially as described.

In testimony whereof we affix our signatures in presence of two witnesses.

GEORGE STABER.
HARTWELL ABBEY.
